Filed Aug. 8, 1966, Ser. No. 3,388

Term of patent 14 years

(Cl. D86—10)

FIG. 1

The essential features of my design reside in the portions shown in full lines on the drawing;

We claim:

The ornamental design for mirror or the like, substantially as shown and described.
